THE COLUMBIA PLANOGRAPH CO., WASHINGTON, D. C.

UNITED STATES PATENT OFFICE.

ARTHUR T. ANDERSON, OF CHAMPAIGN, ILLINOIS.

CONTROLLING DEVICE.

1,310,318.

Specification of Letters Patent.

Patented July 15, 1919.

Application filed March 25, 1919. Serial No. 284,999.

To all whom it may concern:

Be it known that I, ARTHUR T. ANDERSON, a citizen of the United States, residing at Champaign, in the county of Champaign 5 and State of Illinois, have invented new and useful Improvements in Controlling Devices, of which the following is a specification.

This invention relates to controlling devices, for electric motors, particularly to rheostats, and has for its object the provision of latching means for holding the rheostat arm at one limit of its movement when the switch is in its closed position, the latching means being automatically released when the switch is opened so that the rheostat arm will move to the other limit of its movement.

An important object is the provision of a device of this character in which the latching means will be released under the influence of a weight which automatically descends when the switch is moved to open position.

A further object is the provision of a device of this character which will be comparatively simple and inexpensive in manufacture, efficient in use, durable in service and a general improvement of the art.

With the above and other objects and advantages in view, the invention consists in the details of construction to be hereinafter described and claimed and illustrated in the accompanying drawing in which:—

Figure 1 is a front elevation of a controlling device constructed in accordance with my invention and showing the rheostat arm at one limit of its movement,

Fig. 2 is a similar view showing the rheostat arm moved to the other limit of its movement,

Fig. 3 is a cross sectional view showing the switch in side elevation,

Fig. 4 is a longitudinal sectional view 45 through the device, showing the wedge operating means in detail.

Fig. 5 is a detail sectional view on the line 5—5 of Fig. 4,

Fig. 6 is a fragmentary view showing the 50 rheostat handle and its spring,

Fig. 7 is a fragmentary view showing the connection of the operating rod and arm, and

Fig. 8 is a detail sectional view showing 55 the wedge blocks and their guides in plan.

Referring more particularly to the draw-

ing, the numeral 10 designates the casing of my device within which is disposed any suitable arrangement of resistance coils constituting a rheostat, not shown. The numeral 11 designates the rheostat handle which is pivoted at 12 upon the casing 10 and which is movable over a series of contacts 13 arranged in an arcuate row. When the handle engages against the endmost contact 14, the handle is in its neutral position and then engages against a suitable rest or stop 15.

Disposed within the casing 10 is a switch 16 of the double pole single throw type. The wire connections between the switch and the resistance coils forming the rheostat are not shown, as forming no part of the present invention.

In carrying out my invention I provide 75 a transverse bar 17 secured upon the blades of the switch 16 adjacent their pivot points and carrying a downwardly extending arm 18 upon the lower end of which is pivotally secured a wedge-block 19 having a beveled 80 face 20. Disposed within the casing 10 and slideable within brackets 21 secured upon the inner side of the front wall of the casing, is a horizontally disposed rod 22 upon one end of which is secured a wedge-block 23 85 having a beveled face 24 engaging against the face 20 of the block 19. A guide 24^a is provided and includes right angularly extending branches 24^b and 24^c, the former guidably receiving the block 19 and the latter being adapted to guidably receive the block 23 in its movement. A coil spring 25 surrounds the rod 22 and abuts against one bracket 21 and against a washer 26 secured upon the rod 22 whereby the block 23 will 95 always be urged into engagement with the block 19. Connected with the other end of the rod 22 by a slot and pin connection 27 is a vertically extending arm 28 pivotally connected intermediate its ends, as 100 shown at 29, upon the inner face of the front wall of the casing. At its upper end, the rod 28 has a slot and pin connection 30 with a slideable bar 31 movable through a bracket 32 and carrying at its end a head 33 105 having its under surface beveled, as shown at 34.

I further provide a plurality of vertically slideable links 35 movable through brackets 36 and connected with rocking 110 links 37 pivoted, as shown at 38. The upper end of one endmost slideable link 35

2
bears against the beveled surface 34 of the head 33 and the upper end of the other endmost slideable link 35 is bent forwardly, as shown at 39, and extends through a slot 40 5 in the front wall of the casing 10. A weight 41 is secured upon the projecting end 39.

Pivoted at 42 upon the front wall of the casing 10 is a latch bar 43 which has one 10 arm 44 disposed below the weight 41 and which has its other arm 45 provided with a projection engaging a lug 46 extending from the handle 11.

The operation of the device is as follows:—

The parts being in the position shown in Fig. 1 of the drawing, movement of the switch 16 to open position causes swinging movement of the arm 18 carried by the bar 17. As the arm 18 swings, carrying with it the block 19, which moves in its guide 24^b, the spring 25 will cause the block 23 to be moved to the right into its guide 24^c, its inclined or beveled face 24 moving 25 along the inclined or beveled face 20 of the block 19. As the block 23 thus moves, the rod 22 will correspondingly move, which will result in swinging movement of the arm 28 about its pivot 29. When the arm 30 28 is thus moved, the bar 31 will slide to the left, carrying with it the head 33 so that the head 33 will be in non-obstructing position in relation to the upper end of the first slideable link 35. The provision of the 35 weight 41 upon the other endmost slideable link 35 causes a constant upward pressure upon the head 33 so that when the head 33 is moved into non-obstructing position, all the links 35 will slide and the links 37 will 40 rock upon their pivots and the weights 41

will descend. When the weight 41 is thus moved downwardly, it will engage the arm 44 of the latch member 43 and tilt this latch member upon its pivot 42 so that the projection upon the arm 45 will be disengaged 45 from the lug 46 on the handle 11. The handle will then drop to its neutral position, as shown in Fig. 2. When the arm 11 is again placed in its initial position and the switch 16 moved to its closed position, 50 the weight 41 will be automatically elevated so that the latch member 43 will reengage the lug 46 and maintain the handle 11 in vertical position.

While I have shown and described the 55 preferred embodiment of my invention, it is of course to be understood that I reserve the right to make such changes in the form, construction, and arrangement of parts as will not depart from the spirit of the invention or the scope of the subjoined claim.

Having thus described my invention I claim:

A device of the character described comprising in combination, a pivoted controller 65 handle, a pivoted switch, a pivoted latch member engaging said handle, an arm connected with said switch, a slideable rod operatively connected with said arm, a pivoted lever connected with said rod, a train 70 of slideable and pivoted links operatively connected with one another, a slideable bar connected with said lever and serving as a stop for one endmost sliding link of said train, and a weight carried by the other 75 endmost one of said sliding links and disposed in position to engage said latch member.

In testimony whereof I affix my signature.

ARTHUR T. ANDERSON.
